UNITED STATES PATENT OFFICE.

HOWARD H. SHELTON, OF AKRON, OHIO.

MACHINE FOR MAKING COTTERS OR KEYS.

1,151,409.

Specification of Letters Patent. Patented Aug. 24, 1915.

Application filed July 24, 1914. Serial No. 852,963.

To all whom it may concern:

Be it known that I, HOWARD H. SHELTON, a citizen of the United States, residing at Akron, in the county of Summit and State 5 of Ohio, have invented new and useful Improvements in Machines for Making Cotters or Keys, of which the following is a specification.

This invention relates to machines for 10 making spring cotters or keys, and the object of the invention is to provide a machine which will sever blanks from a continuous strip of wire and by a single stroke of a plunger completely fashion the cotters 15 without the necessity of any other operations or the use of any auxiliary mechanism.

The invention contemplates a cutting machine for severing a continuous wire into a series of cotter-forming blanks and simultaneously therewith fashioning the ends of the blanks in a preferred manner such for instance as providing an oblique cut at the ends of the blanks, whereby the finished 20 cotter will be pointed or the cutting mechanism may be so fashioned that the ends of the cotters will be rounded or conoidally-formed during the cutting operation thereby obviating the use of a milling machine on the cotter for rounding the points of the 25 same.

The invention further contemplates the provision of improved machinery for making cotters, whereby after their formation no auxiliary mechanism will be necessary to 30 snugly press the two loose ends thereof together.

With the foregoing and other objects in view, the invention consists in the novel construction, combination and arrangement of 35 parts constituting the invention to be hereinafter specifically described and illustrated in the accompanying drawings which form a part hereof wherein is shown the preferred embodiment of the invention, but it is to be 40 understood that changes, variations and modifications can be resorted to which come within the scope of the matter hereinafter claimed.

In the drawings in which similar reference numerals indicate like parts in the different figures, Figure 1, is a view in side elevation of a machine embodying this invention; Fig. 2, is a plan view of the same; Fig. 3, is a perspective view of the mechanism employed for severing the continuous

wire into blanks; Fig. 4, is a view in side elevation of a gripping jaw for advancing the wire; Fig. 5, is an end elevation of the device shown in Fig. 4; Fig. 6, is a perspective view of the die employed and a blank in operative position just previous to its being formed into a cotter; Fig. 7, is one member of the die shown in Fig. 6; Fig. 8, is a view similar to Fig. 7 showing the blank during the operation of forming it into a cotter; Figs. 9 and 10, are views respectively in side and in transverse section of a portion of the mechanism employed for operating the cotter-forming plunger; Fig. 11, is a perspective view of one form of a finished cotter; Fig. 12, is a perspective view of a blank-holding device; Figs. 13 and 14, are perspective views of dies used for forming the blank, the die shown in Fig. 13 adapted to form a blank with rounded ends and the die 75 in Fig. 14 adapted to cut blanks with obliquely severed ends, and, Fig. 15, is a vertical, transverse, sectional view of the mechanism shown in Fig. 3.

Referring to the drawings in detail, the 80 reference numeral 1 denotes a supporting table provided with legs 2 and further provided with a pair of longitudinally-extending arms 3 having at their outer lower ends journal bearings (not shown) to support a 85 rotatable driving shaft 4. This shaft bears a belt pulley 5 and a pinion gear 6. Also mounted on the upper part of the arms 3 are a pair of journal bearings 7 and 8 in which is mounted a countershaft 9 provided with a 90 key way 10 at one end and it also bears a spur-gear 11 adapted to intermesh with the pinion 6 and receive motion therefrom.

Shiftably mounted in slots 12 in the table 1 is a carriage 13 which is locked against 95 movement through the medium of clamping bolts 14. The carriage 13 bears a projecting arm 15 on which is a journal bearing 16 adapted to hold the hub 17 of a bevel gear 18 on the shaft 9. The hub 17 is provided 100 with a key which engages in the spline 10, thereby compelling rotation of the gear 18 in unison with the shaft 9 while permitting a longitudinal shifting movement of the gear. The carriage 13 also bears a pair of 105 journal bearings 19 in which is mounted a shaft 20 at right angles to the shaft 9. This shaft 20 is provided with a gear 21 which intermeshes with the gear 18 and the opposite end of the shaft 20 is provided with a disk 110

wheel 22 in the front face of which is a radial T-shaped slot 23. The position of the carriage may be shifted on the table at any time by sliding it on the table 1 and it may 5 be locked in position through the medium of the clamping bolts 14, and at all times the gears 18 and 21 will be in mesh and rotation of the shaft 20 assured. Mounted in the radial slot 23 is the enlarged head of a wrist 10 pin 24. Pivotedly attached to the pin 24 is a connecting rod 25. Secured in spaced relation to the front face of the table 1 is a bar 26 constituting a guide for a gripping member denoted generally by the reference number 27. The gripping member (shown best in Figs. 4 and 5) comprises an open faced frame 28 having an upper longitudinal opening 29 and a lower opening 30 separated by a partition 36. The open face of 15 the frame is closed by means of a plate 31. The gripping member is further provided on one face with a projecting stud 32 to receive one end of the connecting rod 25 and which is held in position by means of a nut 33. The opening 30 in the gripping member 27 is adapted to freely receive the bar 26. In the upper opening 29 of the gripping member 27 are a plurality of pairs of spaced pins 34 between the members of each 20 pair of which are gripping rollers 35 which constitute one gripping element of the device, the other gripping member being provided by the partition 36 which extends between the openings 29 and 30. Positioned 25 above the rollers 35 is a horizontally-shiftable cam 37 having a pair of inclined faces 38 arranged to severally engage the rollers 35 and further provided with slots 39 through which extend bolts 40 for guiding 30 and supporting the cam 37. A coiled spring 41 is employed for normally keeping the faces of the cam 37 in frictional engagement with the upper portions of the peripheries of the rollers 35.

45 The wire 42 from which the cotters are formed, is fed from a convenient source of supply, such for instance as a spool, through a wire-straightener 43 of ordinary construction, and is advanced intermittently by 50 means of the gripping member 27 as it reciprocates, the gripping member 27 engaging the wire when the former is at the left end of its stroke in Figs. 1 and 2 and pushes forward the wire a distance which is determined by the position of the wrist pin 24 to 55 vary the length of the stroke of the gripping member 27.

The table 1 is provided adjacent to the gripping member 27 with a slot 44 and 60 mounted on the upper face of the table and above this slot is a base plate 45 for supporting the punching or shearing mechanism for cutting the wire into the blanks as the wire is advanced by the gripping member 27. The punching or severing mecha-

nism comprises a frame 46 provided with laterally-extending arms 47 and 48 preferably formed integral with a base plate 45.

Extending through suitable apertures constituting bearings in the lateral members 47 and 48 is a punch or shear 49 normally held in its upper position by means of a coiled spring 50. Adjacent to the member 46 is a pair of trunnions 51 between the upper ends of which extends a pivot bolt 52 on which is mounted a lever 53 the rear end of which is provided with a roller 54 adapted to run on a cam 56 on the shaft 9. As the shaft 9 rotates it alternately raises the rear portion of the lever 53 and produces a corresponding downward movement of the front end thereof which is positioned over the punch 49 to force the same downwardly. Suitable adjusting means, such, for instance, as a set screw 57, may be provided on the lever 53 to engage the punch 49 for accurately adjusting the amount of movement of the latter. The lower portion of the base plate 45 is provided with a recess 58 in which is a die 59 provided with a notch 60 through which the punch 49 passes in the shearing operation. The base plate 45 is provided with a groove 61 to receive the wire and a similar groove 62 is provided in the die 59 and in alignment with the other groove so that the wire fed forwardly by the gripping member 27 passes along and is guided by grooves 61 and 62 and will be positioned immediately under the punching member 49. The base plate 45 is held in a fixed position through the medium of a clamping bolt 63 extending through the slot 44 for locking the punch and its accompanying mechanism in a predetermined position. If it is desired to form the ends of the blanks obliquely, as shown in Figs. 6, 8 and 11, a die similar to the one shown in Figs. 3 and 14 is employed, wherein the notch 60 is V-shaped, but if it is desired to form the blanks with rounded, tapered or conoidally-fashioned ends, the die is provided with a transverse notch 64 having sides at right angles to the sides of the die and the side walls of the groove 62 are inwardly tapered or conoidally formed at 65 115 so that as a punch suitable for passage through the opening 64 during the cutting operation, will also round and taper the ends of the blanks adjacent to the opening 64.

120 Mounted on the shaft 9 is an eccentric 66 surrounding which is an eccentric strap 67 from which extends a connecting rod 68 the outer end of which is pivotally secured to a pin 69 in a cross head 70. This cross head 125 70 is mounted in suitable guides 71 in a bracket 72 attached to one end of the table 1. Detachably secured to the cross head 70 is a cotter-forming plunger 73 having a reduced end 74; between the reduced portion 130

74 and the main portion of the plunger 73 is a shoulder 75. Mounted on the upper face of the table 1 adjacent to the wire blanks which have been severed from the wire 42, 5 is a guide-block 76 provided with an aperture 77 through which the plunger 73 passes. As shown in the drawing, the severed blanks after the cutting operation, will lie on the upper face of the table and immediately in 10 front of the guide-block 76 and to hold them against accidental movement, a pair of springs 78 are secured to the guide-block 76 by a bolt 79 and the opposite ends 80 of these springs are downwardly-bent and 15 curved to press firmly against the upper faces of the severed blanks and hold them against unintentional movement. Projecting forwardly from the front end of the table 1 is an offset 81 provided with a recess 82 and positioned in transverse alignment with the axial line of the plunger 73. Mounted in the recess 82 is a cotter-forming die 83 preferably composed of a pair of similarly-fashioned members with the cotter-forming recess partially disposed in the 20 upper portions of each of them. The die 83 is preferably provided with inclined upper and lower faces 84 and when positioned in the recesses the lower portions of the upper 25 inclined faces of the dies are adjacent to the blank held by the springs 80. The die-forming recesses in the die members are wider at their rear portions and gradually taper to an approximately cylindrical opening 30 85 formed in their front faces. Immediately above this opening 85 is a slot 86 communicating with the openings. The conformation of the opening 85 and the slot 86 will be approximately similar to the conformation which it is desired to impart to 35 the finished cotter. The side walls and edges of the tapering cotter-forming recess are preferably rounded and their rear portions gradually taper forwardly somewhat 40 conoidally in fashion toward the contracted 45 openings 85. The dies are temporarily held in their seats in the recess 82 through the medium of set screws 87. The upper face of the offset 81 is provided with a pair of 50 apertures on opposite sides of the recess 82 and in these apertures are a pair of L-shaped guiding members 88 which serve to hold the shank ends of the cotters and they are 55 pushed through the contracted portions of the die and hold and guide the same until it has left the machine.

The operation of the device is as follows: 60 Wire, preferably on a spool, is threaded through the straightener 43 in the usual manner and the free end thereof is passed over the partition 36 of the gripping member 27, and under the rollers 35. Motion is then communicated to the device through the medium of the belt pulley which rotates 65 the shaft 9 causing a reciprocal movement

of the gripping member 27 which alternately grips and pushes forward a determined length of wire over the grooves in the base plate 45 of the punch. As the shaft 9 rotates it actuates the punch through the medium of the mechanism described to sever the advance end of the wire lying in the groove 62 and leaves the projecting blank held in position by the springs 80. As soon as the blank has been severed from the continuous wire the plunger 73 is moved forward by the eccentric 66 and the shoulder 75 of the plunger will engage the side edge of the blank as shown in Fig. 6. At the time of the engagement of the shoulder with the blank the reduced pin-like portion 74 projects over the upper face of the blank and serves as a mandrel about which the eye or rounded head of the cotter is fashioned. The plunger forces the blank 80 through the die, as clearly shown in Fig. 8 and as it emerges from contact with the die it completely shapes the cotter so that it is a finished product and requires no further or supplemental treatment to make it a marketable product. 85

It will be noted that if the ends of the blanks are finished obliquely, the ends of the cotters will have a point, as shown in Fig. 11, wherein the cotter is designated by 90 the reference numeral 90. However, if a die blank, such as is shown in Fig. 13, is employed, the ends of the cotter will be rounded as are the common cotters of commerce. By so forming the die 63 the necessity for 95 100 milling the ends of the finished cotters by a separate tool and thus a separate operation is obviated.

It may be pointed out that contrary to the customary practice now obtaining where 105 a number of operations are necessary to finish the cotter, each and every stroke of the plunger 73 will produce a finished marketable cotter or key with the interior face of the head thereof properly fashioned by 110 means of the mandrel 74 and exterior thereof by the cylindrical opening 85 and the ends of the cotter will be brought nicely and snugly together as they leave the die 115 and are guided in their movement out of the die by means of the guide members 88.

I claim:—

A machine for making cotters and the like comprising a forming die provided with a tapering recess terminating at one end in an 120 exit opening corresponding in outline to the complete cotter, a wire-feeding device adapted to intermittently feed wire in front of the entrance opening of said die, means for severing the advanced end of said wire 125 to thereby provide a blank, means to hold said blank temporarily in position in front of said die opening, a carrying mandrel moving transversely to said blank and arranged to force said blank through said die 130

whereby the blank in a plane is bent at right angles to the direction of movement of said mandrel, the end of said mandrel constituting means about which the eye of the cotter 5 is fashioned during its passage through said die.

In testimony whereof I have hereunto set

my hand in presence of two subscribing witnesses.

HOWARD H. SHELTON.
